(57) **CLAIM**

The ornamental design for a shower enclosure, as shown and
described.

DESCRIPTION

In a preferred embodiment, the nature of this product is as an
enclosure for a shower used to wash body parts.

FIG. 1 is a top, right, front perspective view of a shower base
of my new design;

FIG. 2 is a top plan view thereof;

FIG. 3 is a front elevational view thereof;

FIG. 4 is a right side elevational view thereof; and,

FIG. 5 is a top plan view of a shower base according to another
embodiment of thereof.

The broken line representations in the figures are for the
purpose of illustration only, and form no part of the claimed
design.
